UNITED STATES PATENT OFFICE.

FRANK L. BLACKSTONE, OF LINDSAY, CALIFORNIA.

FOUNTAIN PEN.

1,413,893.

Specification of Letters Patent. Patented Apr. 25, 1922.

Application filed April 30, 1921. Serial No. 465,795.

To all whom it may concern:

Be it known that I, FRANK L. BLACKSTONE, a resident of Lindsay, in the county of Tulare and State of California, a citizen 5 of the United States, have invented certain new and useful Improvements in Fountain Pens, of which the following is a specification.

My invention relates to improvements in 10 fountain pens and refers particularly to the self-filling type of fountain pen.

One object of my invention is the provision of a pen of the character stated which will be of extremely simple and inexpensive 15 construction and which will be absolutely positive and reliable in operation and thus insure a pen which will function in a thoroughly efficient and desirable manner.

Another object of my invention is the provision of a self-filling fountain pen, the mechanism of which will be entirely concealed and protected but capable of instant 20 access when desired and which by reason of its few operating parts will not get out of 25 repair or order owing to constant usage and which will thus be entirely practical.

Another object of my invention is the provision of a fountain pen of the self-filling type whose mechanism will be small and 30 compact to occupy a very small space and which will have a large ink carrying capacity and which will function perfectly in the filling of the reservoir as well as in the complete discharge of said reservoir and thus 35 generally provide a fountain pen which will meet every requirement in an article of this character.

With the attainment of the objects stated in view my invention consists of a fountain 40 pen embodying novel features of construction and combination of parts for service substantially as shown, described and particularly defined and distinguished by the claims.

The details of construction embodied in 45 my improvement and the operation of the mechanism will be readily understood and its many features of merit and advantages will be appreciated from the accompanying 50 drawing, in which:—

Figure 1 represents a view partly in section and partly in elevation of a self-filling fountain pen constructed according to my

invention, the parts being in the position they occupy when the elastic container or 55 reservoir is filled and ready for use.

Fig. 2 represents a similar view with the parts in the position they assume when the reservoir has been partially collapsed.

Fig. 3 represents a similar view with the 60 parts in the position they occupy when the reservoir has been completely depressed ready for its suction action to fill said reservoir.

Fig. 4 represents a perspective view of the 65 reservoir engaging member.

Fig. 5 represents a perspective view of the co-operating elastic or spring member which acts in conjunction with said reservoir engaging member.

Fig. 6 represents an end view showing the 70 position of the finger lever for operating the reservoir engaging and the spring member, and

Fig. 7 represents a perspective view of the 75 peculiar shaped finger lever forming a part of my invention.

Referring by numeral to the drawing in which similar numbers of reference are employed to denote like parts in all the views: 80

The numeral 1 designates the body or barrel of the fountain pen which is of hollow construction provided at one end with threads 2, to receive a suitable protecting cap and having mounted in its reduced end 85 3, the pen 4 and co-acting capillary member 5, which parts are of the usual or any preferred construction and disposed in said hollow barrel is the elastic bulb providing the container or reservoir 6, whose outer 90 closed end 7 is disposed near the outer closed end 8 of the barrel or body while the inner open end of the reservoir as usual communicates with the pen and capillary member.

The container or reservoir when filled occupies the position shown in Fig. 1, with the 95 spring strip or reservoir engaging member 9, resting entirely upon the said elastic reservoir, while one end of said member is provided with a curved portion 10, to accommodate its position to the said reservoir, and upon its upper side contiguous to said curved portion 10 is formed with a pair of horizontally slotted ears 11, in which is fitted the 100 ends of the transverse head 12, formed at 105 the inner end of the elastic or spring member

13, whose outer end is formed with a curved spring clip 14, which bears against the barrel of the pen and retains said spring member in proper relation to the reservoir and 5 reservoir engaging member.

From this construction it will be noted that the elastic container or reservoir entirely fills the barrel of the pen and extends practically throughout its length, while the 10 practically rigid engaging member bears against one entire face of said reservoir and upon movement of the angle shaped lever 15, which is pivoted at 16 in the end of said barrel and has one corner pivoted at 17, 15 to said reservoir engaging member, by engagement of the finger with the finger portion 18, of said lever, the said engaging member is first moved to the position shown in Fig. 2 and upon further movement to the 20 position shown in Fig. 3, the reservoir is entirely compressed and upon release or movement of the finger lever to the return position of Fig. 1, the reservoir is completely filled with ink.

25 It will be seen that the action is positive and reliable and that the parts cooperate to completely discharge the ink from the reservoir and as completely produce a suction action to fill the reservoir, the peculiar construction and connection between the lever, the spring member and the reservoir engaging member effecting the desired end.

It will be apparent that I provide a fountain pen which will prove thoroughly efficient and practical in every particular and 35 further, that the construction is such as to insure simplicity, cheapness of production and durability and also the provision of an

attractive and small fountain pen of the self-filling variety.

40

I claim:

1. In a fountain pen, the combination with the barrel or body and the elastic reservoir disposed therein, a lever fulcrumed in said barrel or body, a reservoir engaging member having one end connected to said lever and movable in a longitudinal direction, and an elastic member having its outer end anchored in the barrel and its inner end loosely connected with the inner end of said reservoir engaging member.

45

2. In a fountain pen, the combination with the barrel or body and the elastic reservoir disposed therein, a reservoir engaging member capable of longitudinal movement to depress said elastic reservoir, and a spring member cooperating with said reservoir engaging member, and a finger lever connected with said reservoir engaging member to effect compression of said reservoir.

55

3. In a fountain pen, the combination with the barrel or body and the elastic reservoir disposed therein, a reservoir engaging member capable of longitudinal movement to depress said elastic reservoir, and a spring member cooperating with said reservoir engaging member, and a finger lever connected with said reservoir engaging member to effect compression of said reservoir, said connection between the spring member and reservoir engaging member being at the inner end of said members and permitting an accommodating movement between the same.

60

In testimony whereof I hereunto affix my signature.

FRANK L. BLACKSTONE.
